UNITED STATES PATENT OFFICE

HOWARD M. BARBER, OF PAWCATUCK, CONNECTICUT, ASSIGNOR TO C. B. COTTRELL & SONS COMPANY, OF WESTERLY, RHODE ISLAND, A CORPORATION OF DELAWARE

DEVICE FOR ELIMINATING THE PRINTING OF IMPRESSIONS ON IMPRESSION-CYLINDER PACKINGS

Application filed October 26, 1928. Serial No. 315,304.

One feature of my invention is directed to an improvement in the means for automatically causing the impression cylinder of a rotary printing press to retain the sheet thereon beyond its point of delivery, upon the failure of the sheet feeder to feed a succeeding sheet, thus causing the sheet on the impression cylinder to receive a second impression as it is carried through the press and thereby protect the impression cylinder packing from receiving said last named impression.

Another feature of my invention consists in means for automatically holding the feeding cylinder grippers closed at their point of transfer to the impression cylinder grippers whenever the sheet on the impression cylinder is carried a second time through the press because of the failure of the sheet feeder to present a sheet to the feeding cylinder grippers, thereby preventing the feeding cylinder grippers from tearing or otherwise mutilating the leading edge of the sheet carried by the impression cylinder grippers as it passes by the transfer point and thus preventing the sheet from being properly transferred to the delivery cylinder grippers on the resumption of the operation of the press.

A practical embodiment of my invention is represented in the accompanying drawings, in which

Fig. 1 represents in detail side elevation so much of a rotary printing press as well give a clear understanding of my invention, the parts being in their normal operating positions.

Fig. 2 represents a similar view with the parts in the positions they assume when the feeder has failed to feed a sheet to the feeding cylinder.

Fig. 3 represents a fragmentary view showing the feeding cylinder grippers closed instead of open as they pass the transfer point to the impression cylinder grippers.

Fig. 4 represents a detail end elevation of the parts in the positions shown in Fig. 1.

The impression cylinder of the rotary printing press is denoted by 1, its shaft by 2 and its grippers by 3. The sheet feeding cylinder is denoted by 4, its shaft by 5 and its grippers by 6. The sheet delivery cyl-

inder is denoted by 7, its shaft by 8 and its grippers by 9.

A cam 10 is pivoted at 11 so it may be swung radially out of its normal operative position in the path of the spring pressed gripper operating lever 12 for controlling the operation of the impression cylinder grippers 3, both at their transfer or receiving point from the sheet feeding cylinder grippers 6 and also at their transfer or delivery point to the delivery cylinder grippers 9.

A cam 13 is pivoted at 14 so it may be swung radially out of its normal operative position in the path of the spring pressed gripper operating lever 15 for controlling the operation of the delivery cylinder grippers 9 at their transfer or receiving point from the impression cylinder grippers 3.

These radially movable gripper controlling cams 10 and 13 are connected through the two armed rock lever 16, 17 and rods 18, 19, to move together into and out of their operative positions.

The spring pressed tumbler cam 20, carried by the grippers 6 of the sheet feeding cylinder 4 is operated by the usual tumbler operating pin 21 to close the grippers on a sheet as it is fed in by an automatic sheet feeder of any well known or approved form, the fragments which are shown in the accompanying drawings being denoted by 22. This tumbler cam 20 is normally operated at the transfer point from the feeding cylinder to the impression cylinder by an endwise movable tumbler operating pin 23 to open the feeding cylinder grippers 6 for permitting the sheet to be transferred therefrom to the impression cylinder grippers 3. The grippers 6 normally remain open until they are again closed on the next succeeding sheet fed from the feeder.

A second endwise movable tumbler operating pin 24 is arranged in position to be moved into the path of the tumbler cam 20 as the pin 23 is moved out of the said path in the case where the feeder has failed to present a sheet to the feeding cylinder, thereby holding the grippers closed until they have passed their transfer point to the impression cylinder grippers. The device for moving these

pins 23, 24 endwise simultaneously in opposite directions comprises a pin controlling cam lever pivoted at 25 and having a cam 26 engaging the pin 23 and a second cam 27 engaging the pin 24, the cams being so inclined that as one of the pins is withdrawn from the path of the tumbler cam 20, the other pin will be projected into said path. This pin controlling cam lever is operated by and from the impression cylinder gripper controlling cam 10, hereinbefore described, through a connecting rod 28 secured at one end to an arm 29 of the pin controlling lever and at its other end to the cam 10 at the point 30.

The means which I have shown for controlling the operation of the feeding, impression and delivery cylinder grippers is as follows:

A two armed cam controlling lever 31, 32 carried by the rock shaft 33 has its arm 31 connected by a swinging link 34 to the cam 10 to form a toggle joint connection therewith. The other arm 32 of this lever is normally engaged by one arm 35 of a latch lever pivoted at 36, the other arm 37 of which lever is connected by a rod 38 to the rocking arm 39 of an automatic throw-off mechanism of any well known or approved form, operating in the usual manner to stop the feeder and press when the feeder fails to present a sheet to the feeding cylinder.

A spring 40 tends to hold the latch lever in position to engage the arm 32 of the cam controlling lever and a spring 41 exerts pressure on the arm 31 of the cam controlling lever for breaking the toggle joint connection between it and the cam 10 when the latch lever is released by the operation of the throw-off mechanism for swinging the interconnected cams 10 and 13 radially out of their normal operative positions. A handle 42, carried by the shaft 33 may be used for resetting the cam controlling lever.

In operation:—When, from any cause the feeder fails to present a sheet to the sheet feeding cylinder the automatic throw-off mechanism is operated in the usual manner to stop the feeder and press. The rocking of the arm 39 of the throw-off mechanism will cause the latch lever to rock and swing its arm 35 out of engagement with the arm 32 of the cam controlling lever, thereby permitting the spring 41 to break the toggle joint connection between the cam controlling lever and cam 10 and cause the cam 10 and its connected cam 13 to swing radially out of their normal operative positions in the paths of the impression and delivery cylinder gripper levers 12 and 15 thus allowing the impression and delivery cylinder grippers to remain closed as they pass their transfer point and thereby cause the impression cylinder grippers to retain the sheet on the cylinder and present it in position for a second impression while the press is stopping and thereby protect the impression cyl-

inder blanket from receiving such impression. At the same time the movement of the impression cylinder gripper controlling cam 10 will move the tumbler pin controlling lever to cause it to move the tumbler pin 23 endwise out of the path of the feeding cylinder gripper tumbler cam 20 and the tumbler pin 24 endwise into the said path so that the feeding cylinder grippers will not be opened until they have passed their transfer point to the impression cylinder grippers, thereby protecting the advance edge of the sheet held on the impression cylinder from becoming so torn or otherwise mutilated as to prevent it from being subsequently transferred properly to the delivery cylinder grippers when the press is again started.

It is evident that various changes may be resorted to in the construction form and arrangement of the several parts without departing from the spirit and scope of my invention hence I do not intend to be limited to the particular embodiment herein shown and described, but

What I claim is:—

1. In a rotary printing press equipped with a sheet feeder, feeding and impression cylinder grippers normally coacting to transfer a sheet from the feeding cylinder to the impression cylinder and means, operable when the feeder fails to present a sheet to the feeding cylinder grippers, for holding the impression and feeding cylinder grippers closed as they pass their transfer point.

2. In a rotary printing press equipped with a sheet feeder having an automatic throw-off mechanism feeding and impression cylinder grippers normally coacting to transfer a sheet from the feeding cylinder to the impression cylinder and means actuated by the throw-off mechanism, when the feeder fails to present a sheet to the feeding cylinder grippers, for holding the impression and feeding cylinder grippers closed as they pass their transfer point.

3. In a rotary printing press equipped with a sheet feeder, feeding, impression and delivery cylinder grippers normally coacting to transfer a sheet from the feeding cylinder to the impression cylinder and from the impression cylinder to the delivery cylinder and means operable when the feeder fails to present a sheet to the feeding cylinder grippers, for holding the feeding impression and delivery cylinder grippers closed as they pass their respective transfer points.

4. In a rotary printing press equipped with a sheet feeder having an automatic throw-off mechanism, feeding, impression and delivery cylinder grippers normally coacting to transfer a sheet from the feeding cylinder to the impression cylinder and from the impression cylinder to the delivery cylinder and means actuated by the throw-off mechanism, when the feeder fails to present a sheet

to the feeding cylinder grippers, for holding the feeding, impression and delivery cylinder grippers closed as they pass their respective transfer points.

5. In a rotary printing press equipped with a sheet feeder, an impression cylinder and its grippers, a feeding cylinder and its grippers for normally receiving the sheets from the feeder and transferring them to the impression cylinder grippers and means, operable when the feeder fails to present a sheet to the feeding cylinder grippers, for holding the impression and feeding cylinder grippers closed as they pass their transfer point.

6. In a rotary printing press equipped with a sheet feeder having an automatic throw-off mechanism, an impression cylinder and its grippers, a feeding cylinder and its grippers for normally receiving the sheets from the feeder and transferring them to the impression cylinder grippers and means actuated by the throw-off mechanism, when the feeder fails to present a sheet to the feeding cylinder grippers, for holding the impression and feeding cylinder grippers closed as they pass their transfer point.

7. In a rotary printing press equipped with a sheet feeder, an impression cylinder and its grippers, a feeding cylinder and its grippers for normally receiving the sheets from the feeder and transferring them to the impression cylinder grippers, a delivery cylinder and its grippers for normally receiving the sheets from the impression cylinder grippers and means, operable when the feeder fails to present a sheet to the feeding cylinder grippers, for holding the feeding, impression and delivery cylinder grippers closed as they pass their respective transfer points.

8. In a rotary printing press equipped with a sheet feeder having an automatic throw-off mechanism, an impression cylinder and its grippers, a feeding cylinder and its grippers for normally receiving the sheets from the feeder and transferring them to the impression cylinder grippers, a delivery cylinder and its grippers for normally receiving the sheets from the impression cylinder grippers and means actuated by the throw-off mechanism, when the feeder fails to present a sheet to the feeding cylinder grippers, for holding the feeding, impression and delivery cylinder grippers closed as they pass their respective transfer points.

9. In a rotary printing press equipped with a sheet feeder having an automatic throw-off mechanism, the impression cylinder grippers, their controlling cam movable radially out of its normal operative position and tripping means connecting the cam with the throw-off mechanism whereby the operation of the throw-off mechanism will cause

the cam to be moved out of its operative position to transfer the sheet.

10. In a rotary printing press equipped with a sheet feeder having an automatic throw-off mechanism, the impression and delivery cylinder grippers, their interconnected controlling cams movable radially out of their normal operative positions and tripping means connecting the cams with the throw-off mechanism whereby the operation of the throw-off mechanism will cause the controlling cams to be moved out of their operative positions to transfer the sheets. 70 75

11. In a rotary printing press equipped with a sheet feeder having an automatic throw-off mechanism, the coating, feeding, impression and delivery cylinder grippers, their interconnected controlling cams movable out of their normal operative positions and tripping means connecting the cams with the throw-off mechanism whereby the operation of the throw-off mechanism due to the failure of the feeder to present a sheet to the feeding cylinder grippers, will cause the cams to be moved out of their operative positions to transfer the sheets. 80 85 90

12. In a rotary printing press equipped with a sheet feeder having an automatic throw-off mechanism, the coating, feeding, impression and delivery cylinder grippers, their interconnected controlling cams movable radially out of their normal operative positions and tripping means connecting the cams with the throw-off mechanism whereby the operation of the throw-off mechanism due to the failure of the feeder to present a sheet to the feeding cylinder grippers will cause the cams to be moved out of their operative positions to transfer the sheets. 95 100 105

In testimony, that I claim the foregoing as my invention, I have signed my name this 24th day of October, A. D. 1928.

HOWARD M. BARBER.
